[57] **CLAIM**

The ornamental design for a handle for a bag, as shown and described.

DESCRIPTION

FIG. 1 is a perspective view of a handle for bag showing my new design, the partial showing of a bag in dotted lines being for illustrative purposes only;

FIG. 2 is an enlarged scale side elevational view thereof with intermediate portions on either side of the handle being broken away and omitted for convenience of illustration;

FIG. 3 is a top plan view thereof; and

FIG. 4 is an enlarged scale end elevational view thereof.
